BELT BUCKLE

Filed Aug. 25, 1932

Inventor

Dorsey M. Wirth

UNITED STATES PATENT OFFICE

DORSEY M. WIRTH, OF BUCYRUS, OHIO

BELT BUCKLE

Application filed August 25, 1932. Serial No. 630,886.

The object of this invention is to provide a belt buckle wherein an elastic tensioning means is provided between the buckle and the end of the belt attached thereto for allowing the expansion and contraction of the belt while in position upon the waist of the wearer for thereby preventing the usual necessity of the adjustment of the belt while in use. Another object of this invention is to produce a means for attaching a belt end to this particular style of buckle without it being necessary to retain the spring and yoke parts of the buckle between the belt and its folded back end, and thereby eliminate excessive thickness at this point. By my novel invention the belt end can be attached to this buckle and secured in its natural flat way.

In the drawing;

Figure 1 is a back view of one form of my invention disclosing the manner of attachment, to a belt.

Figure 2 is a detailed view of another suggested form of the spring expansion member which might be incorporated in the form of buckle alluded to in this application.

Figure 3 is a detailed view of a third suggested form of the spring expansion member.

Figure 4 is a detailed view of a fourth suggested form of the spring expansion member.

Figure 5 is a detailed view of a fifth suggested form of the spring expansion member.

Referring to the drawing in detail;

Figure 1 indicates a buckle body 1, of suitable form such as generally rectangular having inturned flanges 2 and 2a on opposite sides, having inwardly directed ears constituting journal mountings. In this figure the belt connector assembly consists of a yoke 6 formed from a single piece of wire which is bent upon itself to form a U-shape member having outwardly extending ends which are journaled in the above mentioned journal mountings of the buckle body; the numerals 10 indicate the ends of the wire. The yoke carries a compression spring 5, and slidably mounted on the arms of the yoke and thru the holes 8 is the belt connector 4, the belt connector being movable against the pressure of the spring; the belt end is passed thru the closed loop end of the connector or fastened

to the connector in any suitable manner. The connector is widened at the points 9 to more securely retain the end of the belt in place. Mounted on the outwardly bent arms of the yoke is the gripping jaw 3 which cooperates with the buckle body for retaining the free end of the belt.

Figure 2 is a modified form of the belt connector that may be attached to the buckle body of Figure 1. This style connector may be a bar or wire bent into the form of a U in which the bight portion is straight, and has the free ends of the legs directed outwardly and then inwardly to form the bends 9, and straightened to come into end to end abutting relation. The permanently attachable belt end is secured upon the portion remote from the bight portion of the connector. This connector 4 is slidably mounted on the arms of the yoke 6 thru the holes 8 in the bight portion of the connector; the coil spring 5 is carried on the yoke for the purpose of a resilient spring action between the yoke and connector. 3 is the gripping jaw.

Figure 3 is another modified form of connector, this connector 4 may be made of sheet metal, one end having an opening thru which the end of a belt is passed and indicated by 7, the other end of the connector having holes 8 in the bent over portions; thru these holes the connector 4 is slidably mounted on the arms of the yoke 6, the yoke carrying a compression spring 5 for a resilient spring action between the connector and yoke; on the outward bent portions of the yoke is mounted a gripping jaw 3. The ends of the arms of the yoke are journaled into the journal mountings of the buckle body.

Figure 4 is a modified form of a yoke that may be substituted if desired for the yoke forms shown in Figures 1 and 2 and 3. The arms 15 are joined by a cross member 11 and surrounding each of the arms between the cross member and the belt connector 4 are expansion springs 5. The connector is slidably mounted thru its holes 8 on the arms 15 and the springs produce a resilient action between the connector and yoke, and mounted on the outward bent portions of the arms 6 is the clamping jaw 3.

Figure 5 is still another modified form of yoke that may be used with the belt connector assembly of either Figures 1 or 2. This is a T shape member, the belt connector 4 is mounted on the arm of the yoke member 16 thru the hole 8, a coil spring is carried on said arm to have one end abut a disk or washer 12 and the other end to abut the belt connector which produces a resilient spring action between the connector and yoke. The fixed end of the belt is passed thru the opening 7. Mounted on the transverse section of the yoke 16 is a gripping jaw 3.

It is believed that the above descriptions and the drawing make clear the nature of my invention and the manner of making and using same.

It is to be definitely understood that I do not desire to limit the application of this invention to the particular modifications set out herein to illustrate the principles thereof, and changes may be made in material or structure or arrangements of parts consistent with the spirit and scope of the invention.

I claim:

1. A belt buckle of the class described comprising a buckle body having flanges thereon, and a belt connector assembly, said connector assembly comprising a yoke having the ends of the member forming the yoke connected with the flanges of the buckle body, a belt connector having one end carried by the yoke, and a belt connecting portion at the other end of the connector, a spring on the yoke cooperating with the belt connector for resisting longitudinal movement of the connector on the yoke, and a belt engaging jaw carried by said assembly for cooperating with said buckle body for retaining the free end of the belt.

2. A belt buckle of the class described comprising a buckle body having flanges thereon, and an expanding belt connector assembly, said connector assembly comprising a yoke having the ends of the member forming the yoke pivotally connected with the flanges of the buckle body, a belt connector having one end slidably carried by the yoke, and a belt connecting portion at the other end of the connector, a spring on the yoke cooperating with the belt connector for resisting longitudinal movement of the connector on the yoke, and a belt engaging jaw carried by said assembly for cooperating with said buckle body for retaining the free end of the belt.

3. A belt buckle of the class described comprising a buckle body having flanges thereon, and an expanding belt connector assembly, said connector assembly comprising a T shape yoke member, the ends of the transverse portion of said member received by the flanges of the buckle body, a belt connector having one end slidably carried by the yoke, and a belt connecting portion at the other end of the connector, a spring on the yoke coop-

erating with the belt connector for resisting longitudinal movement of the connector on the yoke, and a belt engaging jaw carried by said assembly for cooperating with said buckle body for retaining the free end of the belt.

In testimony whereof I affix my signature.
DORSEY M. WIRTH.
